UNITED STATES PATENT OFFICE.

CLAUDE S. SCOBEE, OF WINCHESTER, KENTUCKY.

LUBRICATOR FOR LOOSE PULLEYS.

SPECIFICATION forming part of Letters Patent No. 703,838, dated July 1, 1902.

Application filed September 30, 1901. Serial No. 77,116. (No model.)

To all whom it may concern:

Be it known that I, CLAUDE S. SCOBEE, a citizen of the United States, residing at Winchester, in the county of Clark and State of Kentucky, have invented new and useful Improvements in Lubricators for Loose Pulleys, of which the following is a specification.

This invention relates to a lubricator for loose pulleys, although it will be obvious from 10 the following description that the device can be used with equal facility in conjunction with other types of rotary bodies; and said device is exceedingly simple in construction and is highly efficient in action, requiring but 15 a minimum amount of oil to maintain the contacting parts in properly-lubricated condition. Said device may be made of brass or cast-iron or any other suitable metal, and it includes in its construction a longitudinal per- 20 forated sleeve which fits into the hub of a pulley or similar device and around the shaft carrying such pulley, and said sleeve has a groove extending lengthwise thereof, but closed at its ends, and carries a sleeve suitably fixed 25 thereto, upon which is mounted an oil-containing device, which latter has a conduit arranged to carry the oil to said groove, and the oil leaving the groove reaches through the perforations all parts of the journal and 30 pulley to be lubricated.

It is understood, of course, that I employ the term "oil" in its broad sense to include within its scope any lubricating materials.

The invention is clearly represented in the 35 accompanying drawings, forming a part of this specification, and in which—

Figure 1 is a longitudinal sectional elevation of the lubricator, showing the manner of using the same. Fig. 2 is a front elevation of 40 the device. Fig. 3 is a side elevation of the same. Fig. 4 is a perspective view of a sleeve. Fig. 5 is a detail in plan of a stay-rod.

Like characters refer to like parts in all the figures of the drawings.

45 Referring now to the drawings, the numeral 1 indicates a shaft, and the numeral 2 a loose pulley carried thereby, in connection with which the improved lubricating device is designed to operate.

50 The lubricating device hereinafter described is held against rotation by suitable means hereinafter described, and it includes

a sleeve, as 3, adapted to fit around the shaft 1 and within the hub of the pulley. The sleeve 3 has upon its periphery and extending lengthwise thereof along the top the longitudinal groove 4, which runs practically the full length of the sleeve, it being therefore apparent that the ends of the groove are closed. The groove has in its bottom perforations or 55 holes, as 5. The sleeve has along its opposite sides and in its bottom like perforations or holes, as 6, it being seen that there are three rows of said holes 6, three being in each row, though their disposition and number may be changed. The sleeve has at one end thereof a collar, as 7, held fixedly in place by suitable means, as by the set-screw 8, tapped into said collar and engaging the sleeve, and the latter has in vertical line with 60 said screw a tapped hole to receive the lower threaded end of the tube or conduit 9, depending from an oil-containing device 10, which consists, preferably, of a sight-feed oil-cup. The lower end of the conduit or 65 tube 9 is arranged just over the right end of the groove 4, so that the oil which descends from said cup through said conduit will be delivered into said groove and will pass from said groove through the perforations 70 5 therein onto the shaft 1 and downward and through the lower row of holes 6 to thereby lubricate the pulley, and said oil is carried around by the rotating pulley and caused to pass through the holes 6 in the sides of the 75 sleeve.

The following advantages have been practically demonstrated:

The device requires but an ounce of oil 80 daily to maintain a shaft and pulley constantly lubricated. It obviates the use of Babbitt metal. It protects the shaft, all the wear being on the sleeve, which will last many years and when worn away can be replaced quickly at a trifling cost. By its use the pulley will not become overheated, and it runs noiselessly. A machine does not have to be started in order to lubricate shaft, as the operation is automatic, and the cup need be filled but once a day. Without the use of the 85 lubricator the belt has to be shifted from loose to tight pulley to start operation, and the loose pulley has to be stopped by gripping with hands before oil is applied, by do- 90 95 100

ing which many fatal accidents have been caused.

A stationary standard or post is shown at 15, it being suitably mounted, and an eye at one end of the stay rod or wire 16 embraces the upper end of said standard. The opposite end of the rod or wire has a hook detachably engaging the knob of the cap of the oil-cup 10, this construction serving to hold the 10 lubricator against rotation and being shown in detail only in Fig. 3.

Having described the invention, I claim—

In a lubricator of the class described, a sleeve having a longitudinal groove in its periphery and also having perforations certain 15 of the perforations being in the groove and

the remainder being in the plain or non-grooved portion of the sleeve, a collar separate from the sleeve and fitted thereon, means for holding the collar on the sleeve, and an oil-cup having a straight depending tube the lower end of which is fitted into an opening in the collar, and said opening being located over one end of the groove.

In testimony whereof I have hereunto set 25 my hand in presence of two subscribing witnesses.

CLAUDE S. SCOBEY.
